UNITED STATES PATENT OFFICE.

WILLIAM STEERS, OF BRATTLEBOROUGH, VERMONT.

STEAM-ENGINE.

SPECIFICATION forming part of Letters Patent No. 357,423, dated February 8, 1887.

Application filed January 30, 1886. Serial No. 100,284. (No model.)

To all whom it may concern:

Be it known that I, WILLIAM STEERS, a citizen of the United States, residing at Brattleborough, in the county of Windham and State 5 of Vermont, have invented a new and useful Improvement in Steam-Engines, of which the following is a specification, reference being had to the accompanying drawings.

This invention relates to improvements in 10 steam-engines, which will be hereinafter more particularly described, and pointed out in the claims.

In the accompanying drawings, forming 15 part of this specification, Figure I is an inside view of the steam-chest, showing the valve-plate, and in dotted lines the weight and spring attached to a separate disk on the shaft. Fig. II is a longitudinal vertical section of a part of the engine, showing the valve, weight, and 20 connecting-rod. Fig. III is an enlarged view of the larger end of the valve, which is seen in section, Figs. II and VII. Fig. IV shows an enlarged view of the end and edge of the governor 25 cut-off. Fig. IV^a is a side view of Fig. IV. Fig. V shows the inlet and outlet ports to the valve. Fig. VI is a perspective view of the valve. Fig. VII is a longitudinal vertical section of the engine. Fig. VIII is a transverse vertical section on line x x of Fig. VII. 30 A is a weight pivoted to the plate A" at a. B is a spring, which keeps the weight A in its position, as seen in Fig. I, and is secured to the plate A" at b. The plate A" is of a less diameter than the inside of the steam-chest 35 F, and is secured to the shaft G by a setscrew, f.

C is a connecting-bar, which has one end pivoted to weight A at a', and the other end is pivoted to the governor cut-off D at d.

40 E is a conical valve, secured to the shaft G by a spline, g. The construction of this valve is shown in the perspective drawing, Fig. VI.

D" is the space in which the projecting part D' of the governor cut-off D is fitted, as seen 45 in section, Fig. II. In the figures, e is the inlet-port, e' is the exhaust-port, and e" is the exhaust-pipe.

A' is the valve-plate, in which are the inlet-ports e e e, leading from the steam-chest F and 50 into the passage l to the cylinders, and also the outlet-ports e' e' e', which communicate with the exhaust-passage e".

H is the oil-chamber in the bottom part of the engine, and as the crank K revolves it dips 55 into the oil at every revolution. H' is an air-

space between the outer shell, M, and crank-cylinder N.

l is the inlet-opening to the head of the piston J' in each of the three steam-cylinders III. 60 J J J are the connecting-rods from the pistons J' J' J' of the three cylinders to the crank K. As the revolution of the shaft G brings the steam-inlet of the valve to the inlet l of each cylinder, the steam is admitted to the piston-head thereof, and the movement of the 65 plate A" permits the weight A to lower at the proper time, and by the connecting-rod C the cut-off D closes the inlet e, and the exhaust-ports of the other cylinders are opened. When 70 one of the inlet-ports is opened so that the steam presses upon the heads of the pistons in succession, and just when the outlet-ports are opened from the other cylinders, D acts as a cut-off, so that the steam may act expansively. 75

It is evident that according to the velocity of the revolution of the shaft will the cut-off act as a governor to cut off the influx of steam, and thus regulate the speed.

The advantage of this construction of valve 80 and the cut-off is that, according to the velocity of the rotation of the shaft, carrying with it the plate A", and the weight A, falling by its gravity, will cut off the steam more or less, and thus act as a governor to regulate the 85 speed.

I claim—

1. In steam-engines, the conical valve E, having inlet and exhaust ports, in combination with the valve-plate A', the connecting-rod C, weight A, and spring B, and the plate A", to which they are attached, and cut-off D, secured to the shaft G, substantially as and for the purpose described. 90

2. In a steam-engine, the combination of the 95 conical valve E, having inlet and exhaust ports, the valve-plate A', having three inlet and three exhaust ports, as described and shown, the weight A, connecting-rod C, and plate A", and three steam-cylinders with their inlet and 100 exhaust passages, and three connecting-rods united on one crank-shaft, substantially as described.

In testimony that I claim the foregoing as my own I hereto affix my signature in presence of two witnesses.

WILLIAM STEERS.
